UNITED STATES PATENT OFFICE.

ALLEN TROUSDALE REED, OF BYERS, TEXAS.

SHOE-FITTING STOOL.

1,139,227..

Specification of Letters Patent. Patented May 11, 1915.

Application filed July 30, 1914. Serial No. 854,122.

To all whom it may concern:

Be it known that I, ALLEN T. REED, a citizen of the United States, residing at Byers, in the county of Clay and State of Texas, have invented certain new and useful Improvements in Shoe-Fitting Stools; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in shoe fitting stools and comprises a simple and efficient means of this nature so arranged that the measurements of the foot of a person may be quickly and readily determined.

The invention comprises various details of construction, combinations and arrangements of parts which will be hereinafter fully described, shown in the accompanying drawings and then specifically defined in the appended claim.

I illustrate my invention in the accompanying drawings, in which:

Figure 1 is a perspective view of a measuring stool made in accordance with my invention, and Fig. 2 is a transverse sectional view on line 2—2 of Fig. 1. Fig. 3 is a sectional view taken on line 3—3 of Fig. 2.

Reference now being had to the details of the drawings by letter, A designates a stool which may be of any suitable size or shape, preferably provided with a seat B, and has an inclined portion C and D designates a plate glass which glass is adapted to receive the foot F of a person with the heel against a cross-piece G of the frame G. Underneath the plate glass is a mirror H, affording means whereby the shape of the sole of the foot may be seen by reflection.

Upon either side of the plate glass are the parallel portions O of the frame upon which a graduated scale is formed, the numerals of the scale being designated by letter N. A cross bar L has angled plates L' secured at its ends which plates rest upon and move over said scale. Bar L is provided for the purpose of determining the length of the foot when the latter is positioned as shown

in Fig. 1 of the drawings. Bars Q are adapted to rest upon and are movable with angled plates L' which are supported upon the parallel portions O and each plate L' has a projection O², threaded at its upper end to receive a winged nut O' and each of the projections O² passes through one of the elongated slots Q' which are formed one in each of the bars Q and form means whereby the latter may be held in different adjusted positions. Rising from the bars Q are the two graduated scales S at right angles thereto and to one of which an eye bolt R' is fixed which bolt is adapted to receive one end of a graduated scale R which latter rests upon a screw R² upon the other scale S.

A closure, designated by letter T, which is mounted upon the frame of the device, has a mirror T' therein, whereby the foot of the person may be seen by reflection and buffers T² are placed upon the frame and afford means for preventing the mirror T' from being broken when the closure T is thrown down to cover the plate glass.

The operation of my invention will be readily understood and is as follows: When it is desired to measure the foot of a person, the foot is placed upon the plate glass with the heel against the line G and the length of the foot is determined by the movement of the bar L against the end of the toe of the foot being measured. The plates L' on the bar L will register over the scale at the edge of the glass and the size of the instep is determined by the strap R and the part S, the distance between the heel and the ball of the foot being determined by the registration of the bar Q over the scale at the side of the frame, while the mirror underneath the plate glass serves as a means for showing the person the shape of the sole of the foot.

By the provision of a device made in accordance with my invention, it will be noted that a simple and efficient device is afforded whereby the measurements of a foot may be readily determined in order to secure a proper fit.

What I claim to be new is:

A shoe fitting stool having an inclined frame with glass therein, angle plates engaging over the edges of said frame and provided with threaded projections, slotted measuring bars through which said projec-

tions are adapted to pass, nuts fitted upon threaded ends of said projections for holding the slotted bars in adjusted positions, a measuring bar rising from the inner end of 5 each of said slotted measuring bars, and a measuring bar connecting the upper ends of said measuring bars which rise from the inner ends of said slotted bars and adapted

to pass over the instep of a foot to be measured.

In testimony whereof I hereunto affix my signature in presence of two witnesses.

ALLEN TROUSDALE REED.
